BARREL OR CRATE.

1,391,198.

Specification of Letters Patent. Patented Sept. 20, 1921.

Application filed March 23, 1920. Serial No. 368,069.

To all whom it may concern:

Be it known that we, GEORGE A. LE FEVRE, of Richmond Hill, Queens county, New York, and HUBERT HUTCHINSON, of Newark, 5 Essex county, New Jersey, have invented a new and useful Improvement in Barrels or Crates, of which the following is a full, clear, and exact description.

Our invention relates to improvements in barrels or crates of the kind that are adapted to lie flat for storage, and which can be readily set up preparatory to being filled. Our invention is intended to produce a very cheap, unusually strong and convenient 15 package of this character, and especially one in which if desired the slats or staves of the structure can be placed in close connection so that they will touch at the edges if desired when the container is set up. Our invention is also intended to provide a band or binder on the inner sides of the staves or slats, which will engage hoops extending across the outer parts of the staves or slats in such a way as to hold the parts together 20 for handling or storing, and will at the same time permit the structure to be sufficiently flexible for easy setting up. Our invention is also intended to provide an inside band or binder which will have a sliding connection with the exterior hoop, so that the hoop 25 may be tightened and moved transversely of the slats and with relation to the binder, and thus obviate any straining or displacing of the slats or staves, while it will serve the purpose of securing them firmly to their 30 heads. All of which will be more clearly understood from the description which follows.

Reference is to be had to the accompanying drawings forming a part of this specification, in which similar reference characters indicate corresponding parts in all the views.

Figure 1 is a side elevation of a barrel 45 embodying our invention.

Fig. 2 is a broken plan of the structure when laid out flat showing the inner side thereof.

Fig. 3 is a view similar to Fig. 2 but showing the exterior of the structure.

Fig. 4 is a detail showing how the inner band or binder can be secured at the end.

Fig. 5 is a detail of the means for fastening the ends of the outer hoops together.

Fig. 6 is a view of the fastening when 55 completed, and

Fig. 7 is a section on the line 7—7 of Fig. 6.

The structure is made up of parallel slats or staves 10 which can if desired be provided with the ordinary croze grooves 11 near the ends to receive the heads. This is the usual structure of such containers. Extending transversely of the slats or staves and on the outer sides thereof, are hoops 12 60 which are preferably of flat metal, and any desired number of these hoops can be used. These hoops are adapted to slide lengthwise of themselves, and their ends can be fastened together in any convenient way, but 65 preferably by the fastening shown in Figs. 5 to 7. As here illustrated, one end of a hoop is passed through a loop 13 and doubled back upon itself as shown at 12^a. This overlies an H-shaped clip 14, the arms 15 70 of which extend as shown in Fig. 5 at right angles to the line of the hoop 12. After the end 12^a of one hoop has been bent back as shown in Fig. 5, the adjacent arms 15 of the clip are doubled over upon it, thus 75 fastening the hoop end and clip together. After this the extreme end of the hoop is doubled back upon the bent arms 15, as shown at 12^b in Figs. 6 and 7. This being 80 done, the opposite end of the hoop is drawn 85 taut through the loop 13 and then fastened precisely as above described. This makes a very strong fastening and one which can be easily manipulated either to secure the hoop or to release the ends. 90

To fasten the slats or staves in parallel relation and permit the adjustment of the hoops 12 lengthwise of themselves, we preferably employ an inner band 16 which is preferably in the form of a flexible wire, 95 and this is bent over the outer side of the hoop 12 so as to extend inward between the slats, and is then continued diagonally across the slat as shown in Fig. 2, thence bent outward and around the outer side 100 of the hoop, then inward between the slats and across the next hoop, and so on, forming a series of keepers "a" which extend across the outer part of the hoop at a point opposite the junction of the slats, and members "b" which extend across the inner part of the slat from one member "a" to the next, as the drawing clearly shows. Thus the 105

slats and hoops are securely fastened together, forming a belt-like structure, and at the same time the hoops 12 are capable of longitudinal movement. If desired the parts 5 "b" of the binder or inner band can be arranged directly in the croze grooves 11 near the ends of the slats, as this arrangement prevents any possible slipping of the slats or staves endwise of themselves. The ends 10 of the binder 16 can be fastened in any convenient way to the adjacent slats, and in Fig. 4 we have shown an end portion "c" doubled back upon itself across a slat 10, but this is unimportant.

15 When a structure of this sort is laid flat the slats can be pushed up close together, and when rolled up around their heads to the form shown in Fig. 1, the inner edges of adjacent slats will meet, forming a substantially tight and strong structure, and the structure is flexible enough to permit this rolling arrangement. The ends of the outer hoops can then be fastened as indicated, and in this way a very strong, convenient, and simple container is made.

Obviously if the package is not cylindrical, a rectangular head 17 can be used and the body portion of the structure bent around it, or the head can be given any 20 other preferred shape. In Fig. 8 we have shown a packing case made in this way, and in order that the package may not open 25 too much when the lid is raised, the slats near the top and bottom edges of the head 30 can be nailed as shown at 18, if desired, or otherwise fastened. We have shown this 35 form of container simply to illustrate the fact that the body portion of the structure can be shaped around any suitable head, 40 but of course if the head is rectangular the slats must be of such width as to bring the corners of the head opposite the meeting 45 points of two adjacent slats.

We claim:—

45 1. A structure of the kind described having a body portion formed of parallel slats, flexible hoops extending across the outer parts of the slats, means for fastening the hoop ends together, inner bands or binders 50 extending across the inner parts of the slats opposite the hoops, and a connection between the inner bands and the outer hoops which permits the hoops to slide endwise of themselves.

2. A structure of the kind described having parallel slats or staves and outer hoops extending across the several staves, and characterized by inner bands or binders which follow the inner contour of the several staves, and have a sliding connection 60 with the external hoops.

3. A structure according to claim 2, further characterized by the fact that the inner bands or binders extend between the several slats and around the outer parts of 65 the hoops.

4. In a structure of the kind described, the combination with the parallel slats, of an external hoop crossing the several slats, and an inner flexible band or binder extending transversely across the inner parts of the slats and between the slats and around the outer parts of the hoop thereby forming a connection with the hoop which permits the latter to slide longitudinally.

5. A structure of the kind described comprising a series of parallel slats adapted to be brought into close connection edge to edge, hoops extending transversely across the outer parts of the slats, means for fastening the hoop ends together, and binding wires extending across the inner parts of the slats opposite the outer hoops, each wire extending across each slat and being formed into a series of loops passing between adjacent slats and over the outer hoop.

6. A structure of the kind described comprising parallel slats, flexible hoops extending transversely across the slats, means for fastening the hoops to the slats in a manner to permit the hoops to move longitudinally of themselves, and means for fastening the hoop ends together.

7. A structure of the kind described comprising essentially straight parallel slats, external hoops crossing the slats on the outer side, means for fastening the hoop ends together, and a flexible inner binder extending diagonally across each slat and in a single loop over the outer hoop, whereby the 100 slats can be drawn into close abutment and the hoops can slide longitudinally of themselves through the several loops.

GEORGE A. LE FEVRE.
HUBERT HUTCHINSON.
